HANDLE FOR CARRYING AND STORING DATA BINDERS

John L. Sullivan, Floral Park, N.Y., assignor to The
Mead Corporation, Dayton, Ohio

Filed Jan. 24, 1972, Ser. No. 220,541

Term of patent 14 years

Int. Cl. D8—06

U.S. Cl. D8—154

FIG. 1 is a perspective view of a handle for carrying and storing data binders embodying my new design;

FIG. 2 is a side elevational view showing the side opposite that seen in FIG. 1;

FIG. 3 is a top plan view;

FIG. 4 is a bottom plan view;

FIG. 5 is an elevational view looking from the left of FIG. 2;

FIG. 6 is an elevational view looking from the right of FIG. 2;

FIG. 7 is a perspective view showing a modified form of my new design; and

FIG. 8 is an end elevational view thereof.

I claim:

The ornamental design for a handle for carrying and storing data binders, substantially as shown and described.
